Patented Jan. 2, 1912.

UNITED STATES PATENT OFFICE.

WILLIAM E. PEADEN, JR., OF CORBETT, FLORIDA.

CIRCULAR CUTTER.

1,013,845.

Specification of Letters Patent.

Patented Jan. 2, 1912.

Application filed March 24, 1911. Serial No. 616,578.

To all whom it may concern:

Be it known that I, WILLIAM E. PEADEN, Jr., a citizen of the United States, residing at Corbett, in the county of Santa Rosa and 5 State of Florida, have invented certain new and useful Improvements in Circular Cutters, of which the following is a specification.

The present invention relates to improvements in circular cutters, and is especially designed for cutting friction disks, such as washers, gaskets, etc. of leather, rubber or similar material. The device or tool is also applicable for use as a scribe in marking 15 circular lines or curves.

The essential object of the invention is the provision of a tool for the above purpose which is simple in construction, comparatively cheap in first cost, durable, proficient 20 in use, and capable of facile manipulation in adjusting it for different operations, for instance, in cutting disks of different diameters.

The invention consists substantially in 25 the novel combinations and arrangements of parts as hereinafter described and claimed and as illustrated in the drawings.

In the accompanying drawings I have 30 illustrated an exemplifying structure constructed according to the best mode I have so far devised for the practical application of the principles of the invention.

Figure 1 is a plan view of the complete device. Fig. 2 is an elevation view, one of 35 the beams being shown in section, for convenience of illustration. Fig. 3 is a detail sectional view illustrating the means for securing the cutting blade to a beam. Fig. 4 is a detail perspective of portions of the 40 beams.

The tool is adapted for manual use in connection with the common type of brace, a portion of which is indicated in dotted lines at A, Fig. 2; or power may be applied and 45 the tool actuated in connection with a drill press.

The tool is exceedingly simple in construction and comprises a shank B, a pair of duplicate beams C, C, and a securing wedge key D. The shank is formed at its lower 50 end with a needle point E, and at its upper end with a squared portion F, the latter for engagement with the socket of the hand brace or power drill press. Each beam C,

as are also the other elements of the instrument, is preferably made of tool steel, and the beams are formed with complementary mortises C' C'. Each beam is equipped with a pair of slides G having an integral leg G', the end of which is tempered as required and fashioned into a comparatively broad flat cutting blade or knife H, for the purpose of cutting or scribing. A set screw I is provided for each slide for adjustably securing the knife in desired position, the 60 screw securely clamping the parts together as clearly shown in Fig. 3. The beams C, C, are disposed at right angles to each other, and are seated in the diametrically arranged slots K and K' of the shank, the lower face 70 of the lower beam resting upon the lower wall L of the slot K. The upper wall M of the slot K' is inclined upon a line complementary with the wedge face N of the key D.

It will be noted that the knives may be 75 adjusted to different distances from the center of the beam. For instance, in Fig. 2, considering only the knife at the left, the blade is set to cut a circular disk approximately six inches in diameter, with the point 80 E as a center. If it is desired to cut a disk with an open center, the knife at the right in Fig. 2 is used in conjunction with the first mentioned knife. By the use of the two knives, a disk six inches in diameter, with 85 an open center approximately three inches in diameter is cut. By the use of four knives as in Fig. 1, two open center disks may be cut, the outside diameter of the inner disk being the same as the inside 90 diameter of the outer disk, and the inner disk also having an open center, leaving a third disk cut from the intermediate disk.

The tool is capable of many variations for different uses, and as above described and 95 illustrated in the drawings fulfills the purpose set forth as the object of my invention.

Having thus fully described my invention, what I claim as new and desire to secure by Letters Patent is:—

1. A tool as described comprising a slotted shank, a pair of beams angularly disposed in the slotted shank and a wedge key for securing the parts together, and a series of slides adjustable on the beams each having a cutting edge.

2. A tool as described comprising a shank having diametrically disposed slots, a beam

in each slot and adjustable means for securing the parts together, and slides on the beams, each having a set-screw and a cutting edge.

5 3. A tool as described comprising a slotted shank, a pair of beams formed with complementary mortises, angularly disposed in the slotted shank and a wedge key for securing the parts together, and a series of

slides adjustable on the beams each having 10 a cutting edge.

In testimony whereof I affix my signature in presence of two witnesses.

WILLIAM E. PEADEN, JR.
